(57) **CLAIM**

The ornamental design for a network device enclosure, as shown and described.

DESCRIPTION

FIG. 1 is a front perspective view of the network device enclosure.

FIG. 2 is a front elevation view of the network device enclosure.

FIG. 3 is a right side elevation view of the network device enclosure. The left side elevation view of the network device enclosure is a mirror image of the right side elevation view of the network device enclosure.

FIG. 4 is a rear elevation view of the network device enclosure.

FIG. 5 is a top view of the network device enclosure; and, FIG. 6 is a bottom view of the network device enclosure. The broken lines shown in the figures that are immediately adjacent to the areas included in the claim and define unshaded regions represent the bounds of the claim. Broken lines shown within broken line boundaries are directed to environment. The broken lines form no part of the claimed design.
